UNITED STATES PATENT OFFICE.

THEODORE POUILL, OF BIRMINGHAM, ALABAMA.

ROOF-CROWN FOR OPEN-HEARTH FURNACES.

1,214,066.

Specification of Letters Patent. Patented Jan. 30, 1917.

Application filed July 18, 1916. Serial No. 109,935.

To all whom it may concern:

Be it known that I, THEODORE POUILL, a citizen of the United States of America, residing at Birmingham, in the county of 5 Jefferson and State of Alabama, have invented certain new and useful Improvements in Roof-Crowns for Open-Hearth Furnaces, of which the following is a specification.

10 My invention relates to a roof crown for open hearth furnaces, and its object is to provide a crown which is movable to accommodate itself to the expansion and contraction of the furnace and which will be 15 non-collapsible because the crown blocks will be so held in place that they will not fall out and interrupt the furnace operation or necessitate repairs while the furnace is hot.

20 According to my invention, the crown is built over a wooden center in accordance with the present practice, except that it is my purpose to reduce the rise of its arch to from twelve to eighteen inches so as to 25 keep the gas closer to the bath. I provide means to positively hold the crown blocks in position, and to this end I provide blocks which are substantially deeper than those in current use, and I provide them 30 on each side with rabbets disposed near their upper ends and in position to form chases over the arch between adjoining rows of blocks. Through these chases I pass steel 35 retaining bars which have ample clearance in the chases and are protected from the heat by strips of asbestos extending along the bottom of the chases. The rows of crown blocks at their ends bear on skew backs and the ends of the steel retaining 40 bars rest freely on the skew backs or like supports so that when crown expansion takes place the bars are free to move toward the center of the crown and when contraction takes place the crown and the bars will 45 come back to initial position without collapse. The flat arch which my construction allows provides more head room between the crown and the buck stay girders and this enables me to increase the depth of the 50 crown blocks, bringing their upper rabbeted ends above the skew backs so that the steel retaining bars will rest on the skew backs as the preferred supports therefor.

55 A further object of my invention is to design a crown that will stay in position so

that the furnace can be relined without interfering with or removing the roof crown and to this end I use heavy thick crown blocks keyed together by the steel bars and I provide angle irons or channels on each side secured to the buck stays and adapted to hold the skew backs in position and thus to support the arch independently of the furnace lining.

60 My invention also comprises the novel details of construction and arrangements of parts, which in their preferred embodiment only are hereinafter more particularly described by reference to the accompanying 65 drawings, in which:—

Figure 1 presents a vertical transverse section through the furnace. Fig. 2 is an enlarged vertical cross-sectional view of a portion of the crown. Fig. 3 illustrates a 70 novel type of skew back and shows the crown blocks and a supporting bar in elevation. Fig. 4 illustrates the change in position of the parts when the crown is expanded, as shown in dotted lines, Fig. 1.

75 Similar reference numerals refer to similar parts throughout the drawings.

In Fig. 1 I illustrate an open hearth steel furnace 1 having a lining of magnesite 85 bricks 2 and silicate bricks 3 and an arched roof crown 4 of silicate brick or blocks. The furnace is provided with buck stays 5 connected overhead to the buck stay girders 6 which have their under edge spaced from, and arched to correspond to, the normal arch 90 of the roof crown when expanded. Attached to the buck stays 5 on each side and extending longitudinally thereof from end to end of the furnace are a pair of angle irons 7 and 8 having their horizontally disposed flanges inturned. This inturned flange of the angle 8 is fitted into the alining bottom notches 9 of the row of skew backs 10, and the flange of the upper angle 7 is fitted into alining notches 11 at the upper outer corner of the row of skew backs. These two angles or similar devices on both sides of the furnace serve to support and hold in position the two rows of skew backs 10 independently of the furnace lining.

100 The crown blocks 12 are formed of silicate or other suitable refractory material and are made deeper and thicker than the present type of crown blocks. Preferably they extend substantially above the top of the skew backs against which the transverse rows of crown blocks bear, being keyed at the cen- 105

110

ter with keys all in the manner well understood in the construction of the present roof crowns, except that I prefer to give my crown a minimum of rise as the flatter its arch the closer the gas is held to the bath. To prevent the blocks from falling out or the crown from collapsing, I rabbet the blocks at 13 across their upper side edges. These rabbets are disposed so that the ends 10 of the chases will come substantially level with the top of the skew backs (see Fig. 3). I preferably use a block about eighteen inches in depth and arrange the rabbets about thirteen inches from the bottom end of 15 the block. The rabbets are cut in about two and one-half inches and are given a height of about two inches. When the adjacent rows of blocks are set up the rabbets provide a chase five inches in width and two 20 inches in height extending through the crown above the skew backs. These dimensions are given as exemplary and not as a limit to permissible design. In the chases I insert arched steel bars 14, which at their 25 ends rest on the skew backs and on the upper angles 7 free of fixed connection to either. The ends of the bars, if desired, may be bent straight to rest flat on the top of the skew backs. These bars are preferably of less width than the chase and are of a thickness to leave a substantial overhead clearance in the chase, thus providing for the free expansion and contraction of the bars without any tendency on their part to 30 fracture or injure the crown blocks. To protect the bars from the furnace heat I insert in the bottom of each chase a strip of asbestos 15, preferably having the full width of the chase so that when the rows of blocks 35 are assembled it will form a seal below the bar to prevent the access of heat thereto. In addition to this, the bars, due to the extra depth of the blocks, can be substantially spaced from the furnace heat. In setting in 40 the last rows of crown blocks it is necessary to provide their respective skew backs with a wedge key section 16 which can be forced in to keep the rows in place after the blocks have been set.

45 In practice, the crown blocks are set over a wooden center and the initial weight and supporting strains are taken up in the same manner as with the present crowns. As the arch expands and moves upwardly to dotted line position, Fig. 1, the steel bars 14 will also expand with the crown and their ends will move toward the center of the crown. The bars being left unattached and free to move, as seen in Fig. 4, there will be strain 50 or binding of parts and the crown will be free to expand and contract but the retaining bars will prevent its collapse or the falling out of crown blocks. In the event of the fracture of a block its under portion below the rabbets may fall out but the bar will

support the upper end of the block in position so that no opening will be left in the roof, necessitating an interruption of operation and the bar being set so far up into the deep crown and being protected by such position and by the asbestos strip beneath it from the furnace heat, will not be burned out under ordinary conditions. 70

When it is desired to reline the furnace, its side walls can be removed and replaced 75 without disturbing the crown, which will be held in position by the angle irons 7 and 8 which support the skew backs. By leaving ample space in the chases above the bars 14 for their free expansion and contraction, I 80 not only protect the blocks 12 from a tendency to be fractured by the bars, but I also protect the asbestos strips 15 from being unduly worn or broken by the expanding and contracting movements of the bars. 85

Having thus described my invention, what I claim as new and desire to secure by Letters Patent, is:—

1. In an open hearth furnace, a roof crown formed of arched rows of crown blocks 90 resting at their ends on skew backs, rabbets in the blocks forming arched chases between rows thereof, and floating steel reinforcing bars resting loosely in the rabbets and bearing free or fixed connection thereto 95 on the skew backs.

2. In an open hearth furnace, a metallic frame, an arched roof crown, skew backs disposed along the sides of the furnace with their tops standing flush with a portion of the frame work and left exposed to form a support for reinforcing bars, said skew backs being adapted to support the roof crown, and metallic reinforcing bars the ends of which rest loosely on the skew backs, and said part of the metallic frame and the arched body portions of which contact with and support the arched roof crown, substantially as described. 100

3. In an open hearth furnace, a metallic frame, an arched roof crown, skew backs disposed along the sides of the furnace with their tops standing flush with a portion of the frame work and left exposed to form a support for reinforcing bars, said skew backs being adapted to support the roof crown, metallic reinforcing bars the ends of which rest loosely on the skew backs, and said part of the metallic frame and the arched body portions of which contact with and support the arched roof crown, and means to directly support the skew backs by means of the metallic frame. 110

4. An open hearth roof crown formed of arched rows of crown blocks resting at their ends on skew backs, the crown blocks being vertically elongated to bring their upper ends above the skew backs, rabbets in said upper ends of the crown blocks, and steel bars working loosely in the rabbets 125 130

and bearing at their ends on the upper ends of the skew backs free of fixed connection thereto.

5. In an open hearth furnace, a metallic frame work comprising horizontal longitudinal angle irons, a roof crown formed of rabbeted crown blocks, and arched steel bars extending through the rabbets and resting free of fixed connection on said angle irons 10 to form floating supports for the roof crown that are free to follow its expansion and contraction.

6. An open hearth roof crown comprising crown blocks vertically elongated and rabbeted near their upper side walls, said rabbets forming in adjoining rows of blocks arched 15 chases extending from side to side of the furnace, skew backs supporting the rows of blocks, and arched steel retaining bars inserted in said chases, said bars having lateral and overhead clearance in the chases.

7. An open hearth roof crown comprising arched crown blocks vertically elongated and rabbeted near their upper edges, 20 said rabbets forming arched chases extending from side to side of the furnace, means for supporting the side edges of the crown, arched steel bars inserted in said chases and having lateral and overhead clearance there- 25 in, and an asbestos strip having substan-

tially the width and length of the chase and disposed therein below each steel bar, substantially as described.

8. In an open hearth roof crown, transverse arched rows of crown blocks having 35 rabbets near the upper ends of their abutting faces forming chases, arched retaining bars extending through said chases and adapted each to positively prevent any adjacent crown block, as a whole from falling, 40 skew backs for supporting the ends of the rows of crown blocks, some of said skew backs comprising a wedge shaped key portion, as and for the purposes described.

9. Roof crown formed of transverse 45 arched rows of crown blocks having tapering side walls and straight end walls, there being rabbets extending transversely across the upper portion of the end walls, arched reinforcing bars, substantially wider than 50 the depth of the rabbet, seated in and extending through the alining rabbets of adjacent rows, and projecting strips resting in the rabbets below the bars, said bars being adapted to support the top of a block 55 in position when its lower part falls.

In testimony whereof I affix my signature.
THEODORE POULL.
